Inventor:

Wallace Durand,

By Drake & Co. Atty's.

UNITED STATES PATENT OFFICE.

WALLACE DURAND, OF NEWARK, NEW JERSEY.

DESIGN FOR A WATCHCASE.

SPECIFICATION forming part of Design No. 23,237, dated May 1, 1894.

Application filed February 28, 1894. Serial No. 501,876. Term of patent 7 years.

To all whom it may concern:

Be it known that I, WALLACE DURAND, a citizen of the United States, residing at Newark, in the county of Essex and State of New Jersey, have invented and produced a new and original Design for Watchcases; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

Figure 1 is a face view of the watch case and Fig. 2 is an edge view of the same, these two views being deemed necessary to fully illustrate the design.

The leading feature of my design consists in the watch-case which is round in plan, is convexly curved at its edges and at the center is substantially flat, the said flat center having fish shaped ornaments, the bodies of which are curved in near correspondence with the round sides of the case.

In said drawings, *a* indicates the watch case which is round in plan, convexly curved at the edges and at the center substantially flat as in Fig. 2. The said flat center part is ornamented by fish shaped figures *b*, *b*, which are oppositely curved, as though swimming in a circle, the concave sides of the figures facing one another and the convex sides corresponding more or less closely with the round sides of the watch. Above the fish shaped figures, *b*, is an ornament, *c*, resembling the zodiacal sign for pisces.

What I claim as new is—

The design for a watch case, substantially as shown and described.

In testimony that I claim the foregoing I have hereunto set my hand this 27th day of January, 1894.

WALLACE DURAND.
